UNITED STATES PATENT OFFICE.

JOSEPH R. CAVANAGH, JOHN B. HANNAN, AND JOSEPH D. CLARKE, OF INDIANAPOLIS, INDIANA.

CAR-RECORD DEVICE.

SPECIFICATION forming part of Letters Patent No. 709,394, dated September 16, 1902.

Application filed June 5, 1901. Serial No. 63,310. (No model.)

To all whom it may concern:

Be it known that we, JOSEPH R. CAVANAGH, JOHN B. HANNAN, and JOSEPH D. CLARKE, citizens of the United States, residing at Indianapolis, in the county of Marion and State of Indiana, have invented certain new and useful Improvements in Car-Record Devices; and we do hereby declare the following to be a full, clear, and exact description of the invention, such as will enable others skilled in the art to which it appertains to make and use the same.

This invention relates to that class of devices which are particularly utilized in connection with systems for keeping a record of the movement and location of railway-cars, and has special reference to improved means for facilitating the keeping of a current as well as a past record of the cars.

Heretofore records of the movement and location of railway-cars have been largely kept in books, which are objectionable not only on account of the expense involved in keeping the same, but also by reason of the rapid accumulation thereof, besides the difficulty in quickly and expeditiously locating the entries.

The present invention obviates all of the objections to the use of books for car-record purposes, while at the same time providing a novel construction and arrangement of parts, which are not only peculiarly adapted for keeping convenient and accurate records of railway freight-cars, but which at the same time are applicable to other record systems, such, for instance, as recording subscriptions to magazines or periodicals and keeping stock or inventory of stores in commercial houses or manufacturing concerns.

In carrying out the above objects the invention particularly contemplates individual record-blocks, whereby records covering a period of years may be readily kept within a comparatively small space and quickly and readily accessible, thus enabling a single clerk to keep a continuous record or history of a given number of cars or such other matter that may be recorded by the system employed by the present invention.

Another object is to effect an improvement in the block for holding the slip or card, so as

to provide a maximum holding capacity, while at the same time entirely obviating the displacement of cards or slips therefrom.

With these and many other objects in view, which will more readily appear as the nature of the invention is better understood, the same consists in the novel construction, combination, and arrangement of parts hereinafter more fully described, illustrated, and claimed.

The essential features of the invention are necessarily susceptible to some modification without departing from the spirit or scope thereof; but the preferred embodiment of the improvement is shown in the accompanying drawings, in which—

Figure 1 is a detail in perspective of one form of the improved record-block illustrating the number of slips or cards held in position thereon. Fig. 2 is a longitudinal sectional view thereof. Fig. 3 is a perspective view of another form of the record-block embodying the present invention.

Like numerals of reference designate corresponding parts in each of the views of drawings.

Each individual record-block essentially consists of a quadrilateral body, which is usually of a comparatively narrow oblong shape, so as to fit within the subcompartments or divisions of the case designed to receive the same. The rectangular or oblong block is designed to be so constructed as to accommodate a number of current records in the form of removable record slips or cards, which are ruled and marked in a way to provide for entering the necessary data for the purpose of indicating the movement and location of the particular car represented by the slip or card set apart for keeping such record, but the general form and use of said record slips or cards is substantially the same as set forth in our Patent No. 692,116, bearing date January 28, 1902.

Referring more particularly to the construction of each record-block, the body 14 thereof is formed in its upper side with a longitudinal card-receiving recess or pocket 16, extending substantially the full length of the block-body, to provide for holding a maximum number of record slips or cards within the comparatively small area of the block-

body itself. The ends of the card-receiving pocket or recess 16 therefore reach very close to the ends of the block-body, and at such ends of the pocket or recess are formed the flat transverse terminal shoulders 17, which serve to properly position the record slips or cards upon the block-body, so as to prevent longitudinal slipping or displacement thereof, and to assist in firmly retaining the slips or cards in position the block-body has arranged slightly in advance of the terminal shoulders 17 the upright holding-studs 18, which are spaced only a short distance from the adjacent shoulder 17 and are adapted to be engaged by the retaining-notches 19, formed in the ends of the record slips or cards 15. With the notches 19 interlocked with the studs 18 lateral displacement or movement of the slips or cards from the block-body is positively prevented. In conjunction with said holding-studs 18 there are associated the guard-flanges 20, projecting over the end portions of the recess or pocket 16 substantially flush with the thickened end portions of the block-body, so as to overhang the ends of the record slips or cards and provide a very secure retaining means for said ends of the slips or cards.

The studs 18 and the guard-flanges 20 may be provided in various ways—such, for instance, as by devices in the form of headed tacks, as suggested in Fig. 1 of the drawings, or by wires fitted to the thickened ends of the block-body and shaped to provide the elements described, as suggested by the modification shown in Fig. 3 of the drawings.

The individual record-blocks are provided

at their front ends with the usual indicating-labels 21 and the pull-pins 22.

From the foregoing it is thought that the construction and many advantages of the record device will be apparent without further description, and it will be understood that changes in the form, proportion, and minor details of construction may be resorted to without departing from the spirit or sacrificing any of the advantages of the invention.

Having thus described the invention, what is claimed as new, and desired to be secured by Letters Patent, is—

1. In a record device of the class described, a record-block consisting of a body having a recess or pocket provided with terminal transverse shoulders, holding-studs and guard-flanges carried by the block, said studs having interlocking engagement with the cards or slips.

2. In a record device of the class described, a record-block consisting of a body having a recess or pocket provided with terminal transverse shoulders, holding-studs arranged slightly in advance of said terminal shoulders, guard-flanges overhanging the end portions of the recess or pocket, and the record cards or slips having notched ends.

In testimony whereof we affix our signatures in presence of two witnesses.

JOSEPH R. CAVANAGH.
JOHN B. HANNAN.
JOSEPH D. CLARKE.
